UNITED STATES PATENT OFFICE.

EDWARD B. CRAFT, OF HACKENSACK, NEW JERSEY, ASSIGNOR TO WESTERN ELECTRIC COMPANY, OF NEW YORK, N. Y., A CORPORATION OF ILLINOIS.

SELECTIVE SIGNALING SYSTEM FOR PARTY-LINES.

1,128,857.

Specification of Letters Patent. Patented Feb. 16, 1915.

Application filed June 29, 1910. Serial No. 569,514.

To all whom it may concern:

Be it known that I, EDWARD B. CRAFT, citizen of the United States, residing at Hackensack, in the county of Bergen and 5 State of New Jersey, have invented a certain new and useful Improvement in Selective Signaling Systems for Party-Lines, of which the following is a full, clear, concise, and exact description.

10 This invention relates to selective signaling systems for party lines and has for its object to provide means in connection with train despatching systems whereby various forms of signals for different purposes may 15 be sent out over the line to the various stations.

It is customary on train wires at certain periods during the day to notify the station operators of the correct time. It is the 20 general practice where Morse is used to spell out the word "time" at a predetermined time and at a certain interval after this word has been sent over the line to send out a predetermined number of dots each 25 dot being sent out at a given instant.

This invention is particularly adapted for use in connection with a system wherein a plurality of way stations on one line are each provided with a selector having a 30 ratchet wheel adapted in response to impulses sent out from a despatcher's station to be rotated to close a circuit through a bell, whereby the bell will be vibrated to signal the operator at the station. In this 35 invention each of the selectors is provided with an extra contact which is closed in response to a different number of impulses than are required to close the circuit for operating the vibrating bell, the closing of 40 said extra contact closing a circuit through the bell whereby said bell operates as a single stroke one in response to impulses sent over the line.

The drawing is a schematic diagram illustrating the arrangement of apparatus and 45 circuits.

In said drawing, 1 and 2 designate the line wires, A a despatcher's station and B one way station on the line, the number of 50 way stations on a line varying. Retardation coils 3, 4 and 5 are connected in the line for the purpose of smoothing out the current impulses which are sent over the line for operating the selectors.

55 As shown each of the way stations B is

equipped with a selector mechanism 10, a signaling bell 11 and a telephone set 12, all in bridge of said line. The selector mechanism 10 comprises a slow and a quick acting magnet 13 and 14 and a ratchet wheel 15 controlled thereby, said ratchet wheel having attached thereto a contact arm 16 adapted in the rotation of said pawl 15 to be brought separately into register with contacts 17 and 18 said contact 18 also acting 60 as a stop for said ratchet wheel for limiting its forward movement. When the contact arm 16 is registering with the contact 17, there will be a circuit completed from one side of the train wire through a conductor 20, the contact arm 16, contact 17, conductor 21, armature 22 of the ringer, conductor 24, the windings of the bell 11 and a conductor 25 to the other side of the line. When completed the circuit above 75 traced forms a path for current through the bell winding and armature which causes said bell to vibrate. When the contact at 18 is closed there will be a different path for the current through the bell 80 magnet which will cause said bell to operate as a single stroke one, this path being traced from one side of the line through conductor 20, the contact arm 16, contact 18, conductor 27, and the winding 85 of the bell magnet to the other side of the line. The contacts 17 of each selector are closed each in response to a different number of impulses depending upon the distance from the despatcher's station while 90 the contacts 18 on all of the selectors are closed by the same number of impulses, the number of impulses required to close said contact 18 being different from the number required to close the contact 17 on any one 95 of the selectors. Separate sending devices are preferably provided one for operating the selector at each station to close the circuit for vibrating the bell, the other for closing the circuits at all of the stations for 100 operating the bell at each station as a single stroke bell. When used as a single stroke bell it is caused to tap by opening and closing the sending circuit by means of the apparatus at the despatcher's station.

105 Referring now to the arrangement of apparatus and circuits at the despatcher's station, it will be noted that the line wires 1 and 2 terminate in front contacts 30 and 31 of impulse relays 32 and 33, the armature of 110

2
said relays being in series with a battery 34. A sender key 35 connected in series with the impulse relays and a local battery 36 through one spring of a switching key 37 is adapted 5 to send the impulses over the line for closing the circuit at the way station for vibrating the bell, while a second sender 38 connected in series with the impulse relays and local battery 36 through the other contact of 10 the key 35 and the back contact of a relay 39 is adapted to step the selectors around to close the circuits for operating the bell as a single stroke one. The relay 39 is adapted to be controlled by a relay 40 to open and close 15 the circuit through the impulse relays when the contacts 18 of the selectors are closed, thereby sending impulses over the line and causing the bell to tap once for every closure of said circuit. The signals may be 20 sent out from the despatcher's office or from some office located at a distance from the despatcher's office.

The operation of the parts arranged as hereinbefore described is as follows. Assuming first that it desired to selectively signal one of the way stations the sending key 35 is operated to send out over the line the exact number of impulses necessary to close the signal for vibrating the bell. The local 25 circuit at the sending station when selective signaling is taking place will be from the local battery 36 through a conductor 50, the windings of the impulse relays 32 and 33, contacts 51 and 52 of the sending switch 35, 30 a conductor 53, the switch 37 and conductor 54 to the other side of the battery 36. When time signals are to be sent out over the line the switch 37 will be thrown to cut the sender 35 out of circuit and the sender 38 35 into circuit. The local circuit will now be from one side of the battery 36 through conductor 50, the winding of the impulse relays 32 and 33, conductor 56, back contact of the relay 39, conductor 57, contacts of the

45 sender 38, conductor 58, the switch 37 and conductor 54 to the other side of the battery. The operation of the sender 38 sends the selector around until the contact 18 is closed current still being maintained on the line through the sending apparatus. Now when 50 the circuit through the time relay 40 is opened and closed it will open and close the impulse relays 32 and 33 which will send current impulses over the line; the selector being now in a position where it can move 55 no farther forward these impulses will have no effect on it except possibly to open and close the contact 18 but will pass through said contact 18 and the bell winding causing said bell to signal with single strokes, the 60 period between the impulses being too short to permit the slow acting magnet of the selector to operate but being of sufficient duration to cause the operations of the impulse 65 relays.

I claim:

In a signaling system, the combination with a sending and a receiving station, of a vibrating bell at said receiving station, a selector at said receiving station adapted in 70 response to differing current impulses to close a circuit either through the armature and winding or through the winding only of said bell, mechanisms at the sending station for sending the differing current impulses for closing the respective circuits of 75 said bell, said mechanisms being adapted to hold current on the line for a period after selection, and electromagnetic mechanism for interrupting the closed circuit of one of said 80 mechanisms.

In witness whereof, I hereunto subscribe my name this 28th day of June A. D., 1910.

EDWARD B. CRAFT.
